Primary Examiner — Kelley Donnelly*(74) Attorney, Agent, or Firm* — Michael J. Weins; Jeffrey E. Semprebon(57) **CLAIM**

The ornamental design for a slat-wall shelf cover, as is shown and described.

DESCRIPTION

FIG. 1 is a perspective view of a slat-wall shelf cover of my new design shown in environment;
 FIG. 2 is top perspective view thereof;
 FIG. 3 is a bottom perspective view thereof;
 FIG. 4 is a front elevation view thereof;
 FIG. 5 is a rear elevation view thereof;
 FIG. 6 is a right side elevation view thereof; the left side being a minor image;
 FIG. 7 is a top plan view thereof;
 FIG. 8 is a bottom plan view thereof; and,
 FIG. 9 is a view of cross-section 9-9 of FIG. 7 thereof.
 The broken lines showing in FIGS. 1, 3, 5, 8, and 9 are for the purposes of illustrating either the environment of the article (FIGS. 1 and 9) or functional features of the article that allow it to interact properly with the environment (FIGS. 3, 5, 8, and 9) only and do not form a part of the claimed design. The broken lines that define the bounds of the environment shown in FIG. 1 also form no part of the claimed design.
